UNITED STATES PATENT OFFICE.

JOHN S. RICHARDSON, OF GIBBS, IDAHO.

TOOTHLESS ATTACHMENT FOR THRESHING-MACHINES.

1,131,086.

Specification of Letters Patent.

Patented Mar. 9, 1915.

Application filed February 21, 1913. Serial No. 749,918.

To all whom it may concern:

Be it known that I, JOHN S. RICHARDSON, a citizen of the United States, residing at Gibbs, in the county of Kootenai and State 5 of Idaho, have invented certain new and useful Improvements in Toothless Attachments for Threshing-Machines, of which the following is a specification.

My invention, which relates generally to 10 threshing machines, more especially refers to improvements in toothless attachments therefor, which operate in conjunction with the cylinder and concave; and such invention primarily seeks to provide mechanism 15 of simple and economical construction so arranged as to utilize to the fullest extent the separating tendencies of the cylinder.

The main object of my invention is to 20 provide attachments for threshing machines, such as will obviate the use of teeth and spikes as separating elements, consequently eliminating such inconveniences which accompany the latter.

Another object of this invention is to 25 provide novel grain-separating mechanism for threshing machines including toothless channel and angle bars for connection with the cylinder and concave, respectively, such as will assure the complete separation of 30 grain from the grain-ears, allow a free and continuous circulation of air, and increase the quality of straw.

A further object of the present device is 35 to provide channel and angle bars, as set forth above, for eliminating use of teeth and spikes as separating elements, the channel bars being carried upon the threshing cylinder in parallel alinement with the axis thereof, while the angle bars are supported 40 in a similar position upon the adjacent concave, thus providing an arrangement of engaging surfaces, such as will assure the complete opening of the grain ears, and allow the grain to fall directly upon the shaker 45 elements, means being provided upon the channel bars for allowing exit of the straw.

A still further object of my present invention is to provide attachment of the foregoing character which obviates the serious 50 inconveniences heretofore encountered in devices of this nature, and to provide a simple and durable construction, such as will assure efficient operation of the entire device.

With the above and other objects in view, 55 my invention relates to such details of con-

struction, and in the arrangement and combination of parts, as will be hereinafter fully described and specifically pointed out in the appended claims.

In describing my invention in detail, reference will be had to the accompanying drawings, wherein like characters denote like or corresponding parts throughout the several views, and in which:

Figure 1 is a perspective view of a threshing cylinder, illustrating my improved channel bars, in conjunction therewith; Fig. 2 is an end elevation of the cylinder, illustrating more clearly the specific construction of my attachment therefor; Fig. 3 is a perspective view of one of the channel bars; and Fig. 4 is a cross sectional view of an angle iron, such as is employed upon the concave of the machine.

Referring now more particularly to the accompanying drawings, wherein is illustrated the preferred embodiment of my invention, I have shown the usual form of threshing cylinder in connection with my invention for sake of clearly displaying the exact application of the latter, and it is to be recognized that my invention may be employed upon cylinders of other forms and constructions without departing from the spirit thereof.

The cylinder which has been illustrated consists essentially in the provision of end members 10 carrying hub elements 11 through the medium of transverse and vertical supporting arms 12. A shaft element 13 connects the parallel alined hubs 11 and generally includes means for actuating the end members revolubly.

My invention consists more essentially in the provision of channel bars 14 which have connection about the periphery of the members 10, as at 15. Spacing elements 16 of suitable diameter are employed for connection with the intermediate portions of the channel bars and serve to normally hold the same in correct parallelism and to prevent displacement thereof when in operation. The channel bars mentioned are further provided with longitudinally-extending ribs 17 which are disposed adjacent the longitudinal sides thereof and serve to provide such engaging faces as will assure a complete separation of grain from the grain ears acted upon. In order to allow a continuous free circulation of air, and provide means for allowing exit of straw, each of the

ribs mentioned is provided with a multiplicity of spaced-apart cut-out portions 18. Other objects of the cut-out portions will be recognized as the description and operation 5 of the device continues. Suitable angle bars are carried upon the concave, (not shown), and are preferably held in parallel relation with the horizontal axis of the cylinder. The concave is in turn supported in close 10 proximity to the cylinder, whereas the engaging faces of the ribs 17 will, upon rotation of the cylinder, be brought in close proximity to the upper engaging faces of the angle bars, this operation efficiently 15 opening the grain ears as will be presently set forth.

The angle bars consist of a body portion 19 provided with suitable apertures, whereby it may be fastened to the adjacent portions 20 of the concave in such manner as to obviate its displacement during operation of the cylinder. Upstanding flange elements 20 are provided upon the body adjacent one of its longitudinal edges, consequently 25 allowing passage of grain therefrom after being separated from the grain ears.

In the operation of my invention, the grain being fed between the cylinder and 30 concave is forcibly brought in engagement between the ribs 17 of the channel bars and flange 20 of the angle bars. This operation will completely open the grain ears in such manner as to allow the grain proper to fall 35 through the concave on to suitable shaker screens, not shown. Other material is then fed between the cylinder and concave, movement thereof being allowed by the cut-out portions 18 in the channel irons, as will be 40 recognized.

The greatest stress is laid upon the sim-

plicity of the present attachment, especially in view of the fact that their toothless construction provides a more durable device, and consequently a more efficient operation. 41

The advantages resultant from the use of my invention will be readily comprehended by those conversant with the crude and unsatisfactory devices heretofore employed in this art. 50

Such changes as are permissible by the subjoined claims may be resorted to without departing from the spirit of my invention.

Having thus fully described my invention, what I claim as new and desire to secure by Letters Patent is:—

1. A threshing cylinder comprising a shaft, hoops positioned about said shaft, and longitudinally extending bars carried by said hoops, said bars being formed of channel bar provided with side flanges tapered for their entire depth and provided with alined cut outs extending the full depth of the side flanges. 65

2. An attachment for a threshing cylinder comprising a bar formed of channel bar having its side flanges tapered throughout their depth and provided with alined cut outs extending the full depth of the flanges. 70

3. An attachment for a threshing cylinder comprising a bar provided with a longitudinally extending flange tapered for its entire depth and having cut outs formed therein and extending substantially the entire depth of the flange. 75

In testimony whereof I affix my signature in presence of two witnesses.

JOHN S. RICHARDSON.
